William Allen, Southfield, and Hubert D. Lewis, Detroit,
Mich., assignors to Lewis Industries, Inc., Detroit,
Mich., a corporation of Michigan

Filed Apr. 30, 1963, Ser. No. 74,670

Term of patent 14 years

(Cl. D14—3)

Fig. 1

Fig. 2

Fig. 3

FIG. 1 is a rear elevational view of a sight-seeing tow cart showing our new design.

FIG. 2 is a side elevational view thereof.

FIG. 3 is a plan view thereof with the roof removed to permit illustration of the interior.

The front end of the cart is substantially the same in appearance as the rear end shown in FIG. 1. The opposite side of the cart not shown in FIG. 2 is substantially the same as the showing in FIG. 2.

We claim:

The ornamental design for a sight-seeing tow cart, substantially as shown and described.
